(57) **CLAIM**

The ornamental design for an unmanned aerial vehicle, as shown and described.

DESCRIPTION

FIG. 1 shows a perspective view showing top, front, and right sides of an unmanned aerial vehicle showing my new design;

FIG. 2 shows a front elevation view thereof;

FIG. 3 shows a back elevation view thereof;

FIG. 4 shows a left side elevation view thereof;

FIG. 5 shows a right side elevation view thereof;

FIG. 6 shows a top plan view thereof;

FIG. 7 shows a bottom plan view illustrating one configuration thereof; and,

FIG. 8 shows a second bottom plan view illustrating an alternate configuration thereof.

The broken lines shown in the drawings illustrate portions of the unmanned aerial vehicle that form no part thereof.

1 Claim, 5 Drawing Sheets
